UNITED STATES PATENT OFFICE

CLYDE E. WALLING, OF LAKewood, OHIO

METAL-WORKING MACHINE

Application filed August 27, 1927. Serial No. 215,864.

This invention relates to metal working machines of the type having relative movement between a tool or cutter and rotary work and wherein the action of the tool on the work is controlled according to a pattern or templet, and although illustrated in connection with a grinding machine it is applicable to lathes and cutting machines generally. It is especially applicable to grinding machines of a type adapted for the grinding of taps, reamers and cutters of any kind and of any desired cutting edge.

One object of the invention is to eliminate the difficult and laborious settings which the present machines require for turning, grinding and shaping of articles generally.

Another object is to permit easy duplication of a great number of such articles, and especially the resharpening of old or worn reamers, cutters and the like accurately to their original shape.

Another object is to nearly eliminate the great number of settings the complicated reamers and the like required with the present type of grinding machines.

In the operation of grinding machines commonly in use, the grinding of reamers or cutters requires a considerable time in the setting of the machine, and since most of their work depends on the personal equation of the attendant very often the simplest of reamers or cutters lack accuracy. In their operation, only skilled labor is used. In connection with special reamers or cutters which have their edges at variable distances from center, grinding is expensive since every change in the edge of the cutter requires a special setting. Because of the number of settings these special reamers or cutters require, they are difficult to duplicate or resharpen accurately when worn out.

With the present invention, the speed of production is not only considerably increased but the most difficult reamers or cutters are so easily and accurately ground in their process of manufacture and in their resharpening, when worn out, that the use of skilled labor for the operation is unnecessary.

In the grinding of taps, reamers or cutters some of them have their edges straight and others are in a form of a spiral. These edges have always some kind of relief which relief may either be straight, circular or concave. In this application the grinding wheel has to be such as to produce the kind of relief that is desired to give to the cutting edge of the article, and to produce the desired grinding edge at the wheel a device similar to the one shown in Patent No. 1,143,337 may be used, but this is immaterial to the present invention.

In the present illustration of the invention the grinding wheel is stationary and the articles to be ground are moved back and forth across the wheel. The piece to be ground is supported by two centers on a sliding bed and in addition one of the centers is movable up and down to vary the position of the edge presented to the wheel according to a cam or templet. But it is to be understood the work could be held stationary and the grinding wheel moved along the same. Also, instead of being held between "centers" the work could be held by chucks, sockets or any other means to permit rotation thereof. With this explanation, it will be clear that the invention is of wide application and no limitation is to be implied from the selection of a particular type of machine for purposes of illustration.

It will be apparent that in the present machine, for cylindrical grinding, the centers are at exactly the same height from the supporting table; while a conical grinding requires the centers to be at different heights.

By means of this machine it is possible to produce by one setting the cutting edges of reamers or cutters of the desired shape, and the settings may be varied indefinitely. And this is accomplished by raising or lowering one of the piece supporting centers, automatically, following predetermined requirements easily developed in a cam.

The invention is illustrated in the accompanying drawing, in which Fig. 1 is a plan of the machine; Fig. 2 is a side elevation thereof; Fig. 3 is an end elevation.

In the drawing, the piece to be ground is

represented at 1, and one end of this piece is supported by a center 2 which is directly held by the sliding carriage 20 of the machine. The other end of piece 1 is supported by the adjustable center 3 which is in turn supported on the carriage by a swinging center arm 4 and a block or center base 6 having a fixed arm 60 to which the arm 4 is connected by pivot 5. The arm 4 terminates in a block or stock 40 for the center 3 of ordinary construction. The center base 6 is adjustably held to the carriage 20 by a fastening bolt 13 the head of which is engaged in a T-slot 21 in the carriage. A follower lever 7 is held by screws 8 and 10 to a lever bracket 9 which is in turn held to stock 40 by an appropriate screw 12 engaging T-block 50 in a T-slot in the side of the stock 40, permitting adjustment lengthwise of the stock. The angle of lever 7 may be adjusted by set screw 11, this being permitted by a slotted opening in lever 7 for the screw 10.

A spring 18, connected between the stock 40 and the arm 60, tends to hold the adjustable center 3 at its lowest point which is limited by an adjustable screw 16 which is tapped through the arm 4 and strikes against the arm 60 and by an adjustable screw 17 set in the block 6 under the stock 40 which rests thereon.

The lower end of the lever 7 is provided with a roller 70 which travels along the surface of a templet or pattern cam 14 screwed to a bracket 15 adjustable thereon in a slot 65 in the front of the bed or frame 66 which is fixed, the bracket being fastened by a screw 57. A cam suitable for the work at hand will be used, and may be changed as desired by the substitution of another cam.

The grinding is done by a wheel 80 which is fixed in position to contact with the work which travels across the wheel.

In the operation of the machine the bed 45 66, bracket 15 and cam 14 are stationary. The carriage or slide 20 is reciprocated by any suitable means, the work piece 1 being carried between the centers which move with the carriage.

The roller 70 follows the cam surface and thereby the lever 7 raises or lowers the center 3 on the pivot 5 according to the shape of the cam and this raises or lowers one end of the work so that the wheel 80 follows the profile of the work. If the work is spiral or has spiral blades it may turn on the centers so that the wheel may follow the angle of the blade. When one blade is sharpened the work is turned to present a new blade to the wheel, and the carriage is then reciprocated as before. It will be seen that the action is automatic along each blade which is ground to the profile determined by the selected cam. The operation therefore involves simply the selection of the

proper cam and the movement of the work back and forth under the wheel, the movable center 3 raising or lowering the end of the work support thereby to shape the work accordingly. As stated above, the work instead of being held between centers may be held in chucks or otherwise, and the chuck or other holder will swing or lift according to the templet to vary the profile of the work. Also, both centers or holders could be moved or movable, to permit the desired traverse of the work. And, also, the wheel or cutting tool need not be stationary, but could be moved, by appropriate means, with respect to the work.

The invention is not limited to the particular features shown and described but the machine may be varied within the scope of the following claims.

I claim:

1. In a grinding machine, the combination of a grinding wheel, a reciprocating carriage provided with holders between which the work is held, one of the holders being relatively fixed and the other being movable on the carriage to vary the angle of the work with respect to the wheel, and templet-controlled means to so move said holder as the carriage travels, said movable holder being pivotally mounted on the carriage on an axis transverse to the line of movement of the carriage to swing toward and from the wheel.

2. In a grinding machine, the combination of a relatively fixed grinding wheel, a reciprocating carriage, a pair of centers on the carriage, between which the work is mounted, one of said centers being axially fixed relatively to the carriage and the other being movable to vary the angle of the work with respect to the wheel, and templet-controlled means automatically actuated by the movement of the carriage to move said other center, the movable center having a support pivoted on the carriage on an axis transverse to the axis of the center.

3. In a grinding machine, the combination of a relatively fixed grinding wheel, a reciprocating carriage having a fixed center thereon, a movable center, a pivot connection between the movable center and the carriage the axis of said pivot being transverse to the axis of the center, and templet-controlled means automatically acquired by the movement of the carriage to swing the movable center on its pivot.

4. In a grinding machine, the combination of a relatively fixed grinding wheel, a reciprocating carriage having a fixed center thereon, a movable center, a pivot connection between the movable center and the carriage transverse to the axis of the center, and templet-controlled means automatically acquired by the movement of the carriage to swing the movable center on its

pivot to make its axis offset to that of the fixed center, the carriage being provided with an arm extending behind the movable center, and the center being provided with an arm extending rearwardly and connected to said arm by said pivot.

5. In a grinding machine, the combination of a bed, a templet fixed on the bed, a carriage slidable on the bed and provided with a pair of centers between which the work is held, one of said centers being movable, a support for the movable center pivotally mounted on the carriage, the axis of the pivot being transverse to the 10 axis of the centers, a lever carried by said support and projecting in position to follow the templet and swing said center as the carriage moves, and a grinding wheel adapted to act on work held between the 15 centers.

6. In a grinding machine, the combination of a bed, a templet fixed on the bed, a carriage slidable on the bed and provided with a pair of centers between which 20 the work is held, one of said centers being movable, a support for the movable center pivotally mounted on the carriage, a lever carried by said support and projecting in position to follow the templet and 25 swing said center as the carriage moves, and a grinding wheel adapted to act on the work held between the centers, and a spring connected to the center support and 30 tending to resist movement thereof.

35 In testimony whereof, I do affix my signature.
